UNITED STATES PATENT OFFICE.

JAMES F. ELLIOTT, OF KELLERMAN, ALABAMA.

DRAWING IMPLEMENT.

Application filed April 15, 1922. Serial No. 552,928.

To all whom it may concern:

Be it known that I, JAMES F. ELLIOTT, a citizen of the United States, residing at Kellerman, in the county of Tuscaloosa and 5 State of Alabama, have invented new and useful Improvements in Drawing Implements, of which the following is a specification.

This invention comprehends the provision 10 of a drawing implement designed to draw circles of any desired radius, and is intended to be used in the place of dividers or compasses now in general use.

More specifically stated, the invention 15 comprises the provision of an instrument of the above mentioned character including a short post provided with means for supporting a pencil supporter which is adjustable radially from the post to determine the radius of the circle to be drawn, the post being 20 equipped with means for rotating the latter, incident to pressure exerted downwardly upon the top of the post.

The nature and advantages of the invention 25 will be better understood when the following detailed description is read in connection with the accompanying drawing, the invention residing in the construction, combination, and arrangement of parts as 30 claimed.

In the drawing forming part of this application, like numerals of reference indicate similar parts in the several views, and wherein:—

35 Figure 1 is a view in elevation of the instrument forming the subject matter of the invention.

Figure 2 is a sectional view taken on line 2—2 of Figure 1.

40 Figure 3 is a fragmentary sectional view taken through the post and its associated cap.

Figure 4 is a sectional view taken on line 4—4 of Figure 2.

45 Referring to the drawing in detail, 10 indicates a short post which is tapered at one end to define a point, and slidable on this post is an arm 11 which projects laterally from the post, and this arm is longitudinally slotted as at 12. 13 indicates the arm slide 50 which is arranged longitudinally of the post 10 as shown. Attached to the post and ex-

erting a downward pressure upon the arm 11 are coiled springs 14, the purpose of which will be hereinafter described. Arranged parallel with the post 10 is a pencil holder 15 which may be of any suitable construction, and this holder slides through the slot 12 of the arm, being of course movable toward and away from the post to any desired position, depending upon the size of the circle to be drawn. The arm is graduated as at 16, indicating different radii, so that the pencil holder can be conveniently shifted to its proper position and subsequently held 60 fixed relatively to the arm through the instrumentality of a set screw 17.

The upper end of the post 10 is threaded as at 18, the threads being arranged at the desired pitch for the purpose of rotating the 70 post incident to the depression of the cap 19. This cap is arranged upon the upper end of the post and is grooved to accommodate the threads 18, so that when the cap is depressed, the short post is given one complete 75 revolution. Interposed between the top of the post and the cap 19 is a coiled spring 20 which serves to hold the cap normally elevated, and the cap is of course depressed 80 against the tension of this spring.

In practice, the pointed extremity of the post 10 is placed upon the paper or other object to be drawn upon, and the pencil holder subsequently adjusted to the desired 85 radius. The cap 19 is then depressed in the manner above described, causing the short post to make one complete revolution in drawing a circle, inasmuch as the arm and pencil holder are rotated with said post. When the cap is released, or in other words 90 pressure removed therefrom, the spring functions to return the cap to normal position. The arm is as above stated, slidable on the post 10 and is held depressed by means of the spring, which permits the beam 95 to give slightly when the post leans to one side or the other in making a circle, thus preventing the pencil from tearing the paper. The instrument in its entirety is very simple in construction and can be conveniently manipulated for the purpose intended. 100

While it is believed that from the foregoing description, the nature and advantages of the invention will be readily ap-

parent, I desire to have it understood that I do not limit myself to what is herein shown and described, and that such changes may be resorted to when desired as fall 5 within the scope of what is claimed.

What I claim is:—

1. A drawing instrument of the character described comprising a short post, a graduated arm slidable on the post and projecting laterally therefrom, said arm being slotted, a pencil holder movable through said slot, a set screw holding said holder fixed relatively to the arm in a given position, yieldable means associated with said post and exerting a downward pressure on said arm, a cap slidable on the upper end of the post, yieldable means interposed between the post and said cap, and means whereby the post

is rotated incident to the depression of the cap. 20

2. A drawing instrument of the character described comprising a short post, a spiral thread about the upper end of the post, a cap slidable on the post and having grooves receiving said threads, whereby said post 25 is rotated incident to the depression of the cap, a yieldable element interposed between the post and cap, an arm slidable on the post and projecting laterally therefrom, said arm being graduated, a pencil holder adjustable 30 longitudinally of the arm, and means for retaining said holder fixed relatively to the arm in a given position.

In testimony whereof I affix my signature.

JAMES F. ELLIOTT.
